UNITED STATES PATENT OFFICE.

HARLEY R. MARKEL, OF COLUMBUS, OHIO.

INSULATOR.

971,683.

Specification of Letters Patent.

Patented Oct. 4, 1910.

Application filed August 18, 1909. Serial No. 512,674.

To all whom it may concern:

Be it known that I, HARLEY R. MARKEL, a citizen of the United States, residing at Columbus, in the county of Franklin and 5 State of Ohio, have invented certain new and useful Improvements in Insulators, of which the following is a specification.

My invention relates to the improvement of insulators and especially relates to that 10 type of electrical insulators shown in my former Patent #878,302 of February 4, 1908, and in which the insulator is formed of two sections of porcelain or similar material, said sections being secured together 15 by a screw or bolt, which is also designed to secure the insulator body to a part of a building or other support.

The objects of my present invention are to provide a two part insulator of improved 20 construction, in which the duplicate members are of simple construction and adapted when properly united to form a substantial integral body; to so construct the sections or 25 members of my improved insulator as to avoid the employment of easily broken projections and to facilitate the formation of said sections.

Other objects of my invention will be more fully pointed out hereinafter.

These objects I accomplish in the manner 30 illustrated in the accompanying drawing, in which:

Figure 1 is a view in perspective of my improved insulator body showing the sections thereof fitted one to the other, Fig. 2 is 35 a central vertical section of the same, Fig. 3 is a view in perspective of one of the sections, and Fig. 4 is a sectional view of a modified form.

Similar numerals refer to similar parts 40 throughout the several views.

In carrying out my invention, I employ two separately formed insulator members or 45 sections 1 of equal size and corresponding shape and construction. Each of these members comprises a block or body, the sides and ends of which are at right angles with each other, the upper side or top of the body being formed near one of its vertical sides 50 with a transverse substantially V-shaped recess 2, the diverging surfaces of which are preferably corrugated, as shown. On opposite sides of the recess 2, the section is formed with comparatively narrow horizontal 55 meeting surfaces 3 which are parallel with the bottom side of the block. From

the inner meeting surface 3, the block is provided with a downwardly and outwardly inclined face or diagonal surface such as is indicated at 4, the latter extending downward 60 to meet the surface of an upper outwardly projecting or horizontally extending shoulder or ledge 5, which corresponds with the upper end portion of the block in which is formed the recess 2. This shoulder or horizontal extension 5 is likewise formed with a transverse substantially V-shaped recess 6 on opposite sides of which are horizontal meeting surfaces 7.

In joining the members 1 of my improved 70 insulator, it will be understood that the inclined faces 4 of said members are brought into close contact one with the other and that the meeting surfaces 3 and 7 of the upper and lower shoulders are likewise made 75 to bear one upon the other, thus producing when the parts are so joined a block-like body which is preferably oblong in form, although it is obvious that the same may be square or of other desirable outline. It will 80 also be understood that as in my said former patent, the recesses 2 and 6 are designed to form when the blocks are secured together, wire holding or clamping ways through which two wires may pass and within which 85 said wires may be securely held. In uniting the members of the insulator block or body, I employ a suitable form of bolt or screw not herein shown, which is designed to pass through opposing vertical openings in the 90 insulator body members, these vertical openings which are indicated at 8 being formed lengthwise of the block and intersecting the inclined surfaces 4 of said block. It will also be understood that the threaded extension 95 of a screw thus employed, may be utilized to enter an adjacent frame member or other insulator support.

It will be observed that in the construction of the members of my improved insulator, I have avoided the employment of the usual number of projecting or interlocking parts and have produced said insulator in a comparatively simple form. It will also be understood that the approximately solid 100 members of the insulator when united with their inclined faces bearing one against the other, form an insulator body of great 105 strength, the members thereof being capable of resisting either a vertical or lateral strain.

The structure shown in Fig. 4 is substantially the same as that shown in the remain-

ing figures except that the line of juncture of the parts is not an inclined one but is vertical at 4° and horizontal at 4° and 7°.

What I claim, is:

- 5 1. A two part insulator comprising correspondingly formed sections adapted to fit one against the other, said sections having opposing wire receiving recesses at different elevations, and inclined abutting faces extending throughout the width of the sections and said sections having opposing fastener receiving openings which intersect said inclined faces.
- 16 2. A two part insulator body comprising correspondingly formed sections, each sec-

tion having one of its faces formed with upper and lower horizontal and parallel shoulder portions, said shoulder portions having wire receiving recesses therein and an inclined face extending throughout the 20 width of the section between said shoulder portions, and means for securing said insulator members in engagement with each other.

In testimony whereof I affix my signature 25 in presence of two witnesses.

HARLEY R. MARKEL.
